Patented May 26, 1903.

UNITED STATES PATENT OFFICE.

EGBERT TRACY BRUNDAGE, OF EAST ORANGE, NEW JERSEY, ASSIGNOR TO
MC CLEARY, WALLIN & CROUSE, OF NEW YORK, N. Y., A CORPORATION
OF NEW YORK.

DESIGN FOR RUG.

SPECIFICATION forming part of Design No. 36,338, dated May 26, 1903.

Application filed April 16, 1903. Serial No. 152,992. Term of patent 3½ years.

To all whom it may concern:

Be it known that I, EGBERT TRACY BRUNDAGE, a citizen of the United States, residing at East Orange, in the county of Essex, State of New Jersey, have invented a new, original, and ornamental Design for Rugs, the figure in the accompanying drawing being a face view of a rug, illustrating said design.

I claim as my invention—

The ornamental design for a rug, as shown. ¹⁰
In testimony whereof I have signed my name to this specification in the presence of two subscribing witnesses.

EGBERT TRACY BRUNDAGE.
